UNITED STATES PATENT OFFICE

JOHN Q. HOLMES, OF ANDERSON, INDIANA, ASSIGNOR TO DELCO-REMY CORPORATION, OF ANDERSON, INDIANA, A CORPORATION OF DELAWARE

APPARATUS FOR MAKING COILS OF INSULATED WIRE

Application filed April 2, 1930. Serial No. 440,974.

This invention relates to the manufacture of wire coils for electrical apparatus and particularly coils made from relatively stiff insulated wire. The present invention relates to certain improvements in a machine for automatically unreeling wire from a supply reel and winding a portion of it into a coil and then severing the coiled portion from the remainder of the wire connected with the supply reel. After having produced 10 coils of insulated wire by a machine of this type, it has been the practice to strip the insulation from the ends of the coil to provide for electrically connecting the ends of the wire to parts of the electrical instrument 15 of which the coil is a part. The present invention provides means for stripping the insulation of the wire being supplied to the machine at portions spaced apart at regular predetermined distances sufficient to provide 20 length for forming the required coil. This stripping means is so coordinated with the coil winding machine that after a coil has been wound it will be severed across the bared 25 or stripped portion of the wire. Therefore, the improved machine will produce insulated wire coils, the ends of which are bare of insulation. Thus, the present improvement does away with the subsequent operation of 30 stripping the ends of the coil after it has been wound in the machine.

Further objects and advantages of the present invention will be apparent from the following description, reference being had to the accompanying drawings wherein a preferred embodiment of one form of the 35 present invention is clearly shown.

In the drawings:

Fig. 1 is a perspective view of a coil winding machine embodying the present invention.

Fig. 1a is a perspective view on a larger scale than Fig. 1 showing a coil produced by the machine.

Fig. 2 is a perspective view of the coil winding machine looking in the direction of arrow 2 in Fig. 3.

Fig. 3 is a plan view of the machine.

100

Referring to Fig. 1a, the coil 30 produced by the present improved machine has an inside layer of turns 31 and an outside layer 32. The inside layer has a start lead or terminal 33 bent at 34 at right angles to the plane of the first turn of the layer 31 so that it will expand substantially parallel with the axis of the coil. The end lead 35 of the last turn of the outside layer 32 extends tangentially to the coil 30 and at right angles to the start lead 33. The coil 30 is wound from relatively stiff insulated wire, preferably wire previously coated with insulating enamel. The start lead 33 has an end portion 33a which is bare of insulation and the end lead has a portion 35a also stripped of insulation.

In order to produce the coil shown in Fig. 1a, the present improved machine provides the following mechanism: means for feeding 20 positively, the wire through a distance sufficient to carry its ends 33b where it was cut off to the bending mechanism for bending it around the portion 34; a mechanism for bending the lead 33 about the portion 34 and 25 for causing said bent lead to be engaged by and connected with the coil winding spindle; a coil winding spindle upon which the layers 31 and 32 are wound and mechanism for causing the spindle to be moved axially while being rotated in order to form the two layers 30 and 32; shears for severing the completed coil from the remainder of the supply of wire; means for guiding the wire from the shears to the winding spindle; a plunger 35 which moves against one end of the winding spindle and follows its movement during the winding of wire thereon and then separates from the end of the spindle so that the coil after having been severed from the supply 40 wire may be removed from the spindle, preferably by gravity; means for ejecting the finished coil from the machine after it has fallen from the spindle; and means for stripping the insulation from portions of the wire 45 at regularly spaced intervals, the insulated portions between the bared portions being sufficiently long to form the required coil, and the stripping mechanism being so related to the wire cutting mechanism that the wire 50 will be cut across the bared portion in order that the end portions of the leads of the coil will be stripped of their insulation before the coil leaves the machine. These mechanisms will be described in detail in the order named.

55 Positive feed of wire

The coil forming mechanism is supported upon a table 40 having legs 41 and supporting bearings 42 and 43 for a main operating 60 shaft 44 which carries a large gear 45 meshing with a smaller driving gear 46 fixed to a shaft 47 which carries a sprocket gear 48 connected by sprocket chains 49 with a driving sprocket gear 50 which is driven by an electric motor 51 through a speed reducing

mechanism located within a case 52. The shaft 44 carries a beveled gear 53 meshing with a light bevel gear 54 mounted on a shaft 55 supported by bearings 56, 57 and 58. The shaft 44 carries a cam 60 shown in Figs. 70 3 and 5 and adapted to engage a roller 61 carried by a rack 62 slidably guided by bearing blocks 63 and 64. The roller 61 is urged towards the cam 60 by a spring 65 having one end attached to a pin 66 fixed to the rack 62, the other end of a pin 67 fixed to the bearing 42. The extent to which the rack 62 may approach the cam 60 depends on the setting of a stop screw 68 adjustably attached to the rack 62 and adapted to engage the stop 80 69 fixed to the bearing 42.

Referring now to Fig. 12, the rack 62 meshes with a gear 70 on a shaft 71, rotatable in bearings 72 and 73 carried respectively by a plate 74 and a bracket 75 to which the plate 85 74 is attached. The gear 70 drives a gear 76 which meshes with a gear 77 loosely rotatable upon a shaft 78 rotatable in a bearing 79 provided by the bracket 75 and an upper bearing provided by the plate 74. The gear 77 carries a pin 81 pivotally supporting a pawl 82 engageable with a ratchet 83 fixed to the shaft 78. The pawl 82 is urged against the ratchet by spring 84 having one end attached to the pawl and the other to a pin 85 attached to the gear 77. The pawl and ratchet device provides for driving the shaft 78 in one direction only. During the backing up of the pawl 82 or rotation in a clockwise direction about the shaft 78, rotation of the shaft 78 in this direction is resisted by a brake comprising a rotatable disc 90 rotatable with the shaft 78 and movable slightly axially thereof. The disc 90 is urged against the stationary top surface of plate 74 by spring 91 located between the disc 90 and a washer 92 held against the spring by the head of the screw 93 which may be screwed into the shaft 78 when it is desired to increase the pressure applied by the brake disc 90 upon the plate 74. The ratchet 83 is integral with the hub 95 of a wire feed roller or wheel 96 which cooperates with a companion roller 97 to feed the wire A when clamped between these rollers. The roller 97 is mounted on a shaft 98 journalled in a bearing 99 slidably in an elongated oblong hole 100 in the bracket 75 and journalled in a 110 slidable bearing block 101 guided by recess 102 in the plate 74 the recess being partly covered by plates 103 which retain the block 101 and shaft 98 in position. The rollers 96 and 97 are provided with cooperating 125 gears 96a and 97a so that the roller 97 will be positively driven. Normally, the roller 97 is held out of clamping position with the wire A due to a spring 104 which urges the block 101 away from the shaft 78 a slight dis- 130

tance, but not to the extent that the gear 97a will be out of mesh with the gear 96a.

When it is desired to feed the wire A, the roller 97 will move toward the roller 96 so that the wire will be ripped between the rollers. This movement of roller 97 laterally is effected by cam 110 fixed to the shaft 55 and engageable with a relief spring lever 111 fixed at 112 having its free end attached to rod 113, having its head end received by a notch 114 of T-shaped cross section provided in the block 101. The cams 60 and 110 are so coordinated that during the time the cam 60 engages the roller 61 to move the rack 62 toward the right as viewed in Fig. 3, in order to effect counterclockwise rotation of feed roller 96 and clockwise rotation of feed roller 97 as viewed in Fig. 3, the cam 110 will cause the roller 97 to be urged yieldingly through the leaf spring lever 111 toward the roller 96 whereby the wire A will be yieldingly gripped between these rollers in order that the wire may be fed toward the right as viewed in Fig. 3, or toward the left as viewed in Fig. 10, or from top toward bottom as viewed in Fig. 9. Referring to Fig. 10, a bracket 220 fixed to the table 40, carries a shear block 221 having a central bore through which the wire A is fed. The block 221 cooperates with a movable shear blade 222 to sever the wire along the surface 221a of the block 221. The mechanism for positively feeding the wire will cause the wire to be fed from the surface 221a to the point 33b₂ which is the location of the end portion 33ax of the start lead of the wire 33a before it is bent into the position 33a shown in broken dash lines in Fig. 10. During the feeding of the wire by the positive means described and also during the winding of the wire following the positive feeding thereof, the wire is unwound from a supply reel 120 mounted on a spindle 121, and the wire is caused to be fed by geared rollers 122 and 123 and through an insulation stripping device 300 to be described later and then between felt cleaning pads, one of which is shown at 124 in Fig. 3 and is attached to the bearing 43, then between felt oiling pads 124 and 125 shown in Fig. 1. Pad 124 is supported by bracket 126 and pad 125 pressed against pad 124 by a leaf spring and supplied with lubricant from an oil cup 127. The wire then passes between rollers 96 and 97 and then through a guide tube 128 fastened to a post 129 and through the bracket 220 which supports the cutting block 221. The geared rollers 122 and 123 are caused to rotate through a mechanism including a shaft 130 which supports the roller 123 and carries a pulley 131 driven by belt 132 connected with a pulley 133 driven by shaft 47 as shown in Figs. 1, 2 and 3.

Coil start lead bending mechanism

The mechanism for bending the coil start lead 33a from the position 33ax shown in dot-dash lines in Fig. 10 to the position 33a shown by dash lines includes a shaft 140 rotatable in bearings 141 and 142 provided by a bracket 143 (see Figs. 9 and 11). The shaft supports coaxially therewith an extension or pin 144 which is located directly below the wire and below a corner edge 145 which is provided by the junction of the annular surface 146 of the coil winding spindle 150 and the longitudinal plane surface 147 of the notch 148 provided in the spindle 150 for receiving the start lead 33 of the wire. The annular surface or shoulder portion 46 is formed by reducing the diameter of the spindle to provide the portion 151 upon which the coil is wound. As stated before, the projection 144 of the shaft 140 is located below the wire A and the corner 145 in order that the wire will be held against the corner 145 while being bent. The bending is performed by a second projecting pin 152 carried by the shaft 140. This pin 152 is rotated in a counterclockwise direction as viewed in Fig. 10 from a position below the end 33ax of the wire A to the position shown in Fig. 10 by a mechanism which includes a rack 153 meshing with an elongated gear 154 integral with the shaft 140. The rack is guided by plates 155 and 156, the ends of which are engaged in suitable grooves in the rack 153. These plates are secured to the bracket 143 by screws 157. Referring to Figs. 6 and 9, the rack 153 is yieldingly urged downwardly by spring 158 having one end attached to the rack and the other to table 40. The rack 153 is moved upwardly in order to bend the wire by lever 159 connected at 160 with the rack 153 and pivoted at 161 upon a bracket 162 and carrying a roller 163 operated by cam 164, the contour of which is shown by dot-and-dash lines in Fig. 7, which shows a tandem view of the cam 164, lever 159 and rack 153. The cam 164 is fixed to a shaft 165 which is supported by bearing 166 integral with bracket 162 and is connected by coupling members 167 and 168 with a shaft 169 journalled in the bearing 170 and carrying a gear 171 meshing with a gear 172 driven by shaft 55 which, as explained before, is driven by shaft 44 through gears 53 and 54. Gears 53 and 54 have the same pitch diameter and likewise gears 171 and 172, hence shafts 44, 55, 169 and 165 rotate at the same speed.

After the bending operation has been performed, it is necessary to withdraw the bending mechanism from the winding spindle 150 before the winding upon the spindle can take place. Hence, the bending shaft 140 is caused to move into a position for performing the bending operation in which position it is held while bending takes place, and im-

mediately following the bending operation the shaft 140 is retracted. These movements of the shaft 140 are effected by cams which control the movement of a lever 175 pivoted at 176 upon the bracket 162 and having a notch 177 for receiving the outer race member of a ball bearing 178 fixed on the end of the shaft 140 by nut 179. As shown in Fig. 7, the lever 175 is engaged by cam 180 which rotates in the direction of the arrow 181 to cause the ball bearing to move from the position 178a shown in dot-and-dash lines, into the position 178 shown in full lines in Fig. 7. Thus the cam 180 cooperates with the lever 175 to advance the bending mechanism into operating position. In order to retract the bending mechanism, the shaft 140 is moved toward the left as viewed in Fig. 7 by a cam 182 which cooperates with the roller 183 carried by the lever 175, said cam 182 being riveted to a cam 235, also driven by the shaft 165. During the motion of the cam 182 in a counter-clockwise direction as viewed in Fig. 7, the roller 183 will be moved into the dot-dash lines of 183a in Fig. 7 in order to retract the bending mechanism from the spindle 150.

Spindle operating mechanism

The spindle 150 is supported for rotary and axial movement by bearings 190 and 191 provided by bracket 192 supported by the table 40. The spindle 150 carries a broad face gear 193 meshing with a gear 194 which is loosely rotatable upon a shaft 195 and is connected therewith by yielding lost motion connection which comprises a spring 196 connected at one end with a rod 197 extending from the hub 198 of the gear 194 and attached to a rod 199 extending from a collar 200 attached to the shaft 195. The spring 196 tends to pull the rods 197 and 199 together until lugs 198a and 200a of the hub 198 and the collar 200 respectively, are held in engagement. The purpose of this yielding lost motion connection is to insure that the spindle 150 will be located with its notch 148 in proper position to receive the wire which is bent into it before the winding operation starts. In order to provide for stopping the spindle 150 at the proper interval, it is provided with a stop lug 201 adapted to engage a stop pin 202 supported by the bearing 191. The spindle 150 is rotated clockwise as viewed in Fig. 4, until the lug 201 strikes the top of stop 202 whereupon the spindle 150 will stop rotating and will be located so that its notch 148 will be located as shown in Fig. 9. This rotation of the spindle 150 is effected by counterclockwise rotation of the gear 194 and hence of the collar 200 and pin 199. The shaft 195 is rotatable through an angular distance counterclockwise greater than necessary than just to rotate the spindle against the stop. Hence, after the spindle has

stopped rotating the rod 199 will continue to move away from the rod 197 a certain distance, thereby increasing the tension in the spring 196 which acts to yieldingly maintain the spindle in the proper position. The amount of lost motion between the gear 194 and the shaft 195 is approximately five degrees.

The shaft 195 carries a gear 204 meshing with a rack 205 which is guided for horizontal movement by the table 40. The rack 205 is pivotally connected at 206 with a connecting rod 207 connected with a crank pin 208 fastened to the gear 45. Therefore, during one rotation of the crank pin 208 the rack 80 will make one reciprocation and the gear 195 one complete oscillation, in order to cause the spindle 150 to rotate first counterclockwise from its normal position in order to wind the wire A thereon, and then to return the spindle to normal position by clockwise rotation during which the coil wire is removed from the spindle.

In order to reciprocate the spindle 150 while it is rotating so that wire may be wound thereon in even layers, there is provided a plate cam 210 fastened to the rack 205 and provided with a shallow B groove 211 adapted to receive a roller 212 supported by a slide bar 213 guided by bracket 214 and pivotally connected with a lever 215 having a bifurcated end 216 each arm of which is provided with a notch 217 for receiving a pin 218 projecting from a collar 219 surrounding the upper end of the spindle 150 and fixed against axial movement along the spindle. It is therefore apparent that during each stroke of the rack there will be two strokes of the spindle. As the rack moves from left to right the spindle 150 will be rotated counterclockwise as viewed in Fig. 4 in order to wind wire thereon and during the winding operation the spindle will be caused to move upwardly and then downwardly in order that two layers of wire 31 and 32 will be successively wound upon the spindle. During the return stroke of the rack the spindle will rotate clockwise to its normal position and will be oscillated making an up stroke followed by a down stroke, but during this second oscillation no wire is wound on the spindle.

Shears for severing the coil

After winding the coil in the manner described, it is next sheared from the remainder of the wire in the machine by a mechanism which will now be described with reference to Figs. 8, 9 and 10 as already described with reference to the operation of the positive feeding mechanism. The wire is cut by the cooperating stationary shear blocks 221 and the removable shear blades 222. The blade 222 is provided on the right hand end of a lever 223 pivoted at 224 upon the bracket 143

and carrying at its left hand end a roller 225 cooperating with a cam 226 fixed on the shaft 165. A spring 227 attached to the lever 223 and to a post 228 on a bracket 229 yieldingly urges the roller 225 against the cam 226 and the shear away from the orifice in the shear block 221.

Means for guiding the wire from the shears to the spindle

10 The means for guiding the wire from the shear block to the spindle 150 comprises a bar 230 slidable in a groove 231 provided by the frame 143 and held in position by a plate 232 secured by screws 233. The bar 230 is provided at its right hand end with a groove portion 234 through which the wire slides while being fed through the shear block 221 to a point beyond the spindle 150. Since the 15 guide 234 must be moved away from the shear block 221 while the shear blade 222 is operating to cut the wire, the bar 230 is automatically actuated into operating position by a cam 235 engageable with a roller 236 pivotally supported by the bifurcated left end 237 of the slide 230 and yieldingly maintained against the cam 235 by spring 238 attached to one end of the spring post 228 and at the other end to a pin 239 fastened 20 to the bar 230 and extending through a slot 240 in the frame 143. Obviously, the cam 235 moves the wire guide member 234 into operating position and the spring 238 moves it 25 into non-operating position.

35 *Means for retaining the coil on the spindle during the winding operation*

In order that the coil 30 which is wound upon the mandrel portion 151 of the spindle 40 will readily drop from said mandrel after the coil has been severed from the wire remaining in the machine, it is desirable that the arbor 151 be no longer than is just necessary to wind the wire thereon, that is, no 45 longer than the coil itself. Therefore, in order that the bottom turns of the coil will be wound properly upon the arbor, the machine provides a plunger 240 which is yieldingly pressed against the lower end of the mandrel 151 and follows the mandrel while 50 the wire is being wound thereon and then descends until its upper end cap 240a is flush with a guide sleeve 241 at a time just before the coil is severed from the remaining wire. 55 Referring to Fig. 6, the mechanism for operating the plunger 240 comprises a cam 242 mounted on the shaft 165 and cooperating with a roller 243 on a lever 244 fixed to a shaft 245 journalled in a bracket 246 attached 60 to the table 40. The roller 243 is urged against the cam 242 by spring 247 attached to the lever 244 to the table 40. The shaft 245 carries lever 248 having a bifurcated end 249 each branch of which has a branch 250 for receiving a pin 251, which extends dia- 65 metrically across a collar 252 and a plunger 240 and within the plunger carries a block 253 for supporting one end of a spring 254, the other end of which bears against the under side of the cap 240a. The plunger 240 is provided with a pair of diametrically opposite slots 255 for receiving the pin 251. The cam 242 imparts such motion to the levers 244 and 248 and block 253 as to cause the spring 254 to be compressed beyond its initial state of compression to an extent such that the cap 240a of the plunger 240 will always be maintained against the bottom end of the arbor 151 while the arbor makes an up and down movement during the winding of a 70 coil thereon. Immediately following the winding of the last turn upon the arbor, the plunger 240 immediately descends so that its cap 240a will be flush with the top of the guide block 241. As the plunger descends 75 the coil is severed from the wire in the machine, the coil unwraps itself slightly from the arbor due to the resiliency of the wire and the coil descends upon a platform provided by the upper end of the cap 240a and the coil 80 is then ready to be ejected.

Coil ejecting means

Referring to Figs. 10 and 11, the coil ejector comprises a U-shaped pusher 250 mounted to 95 slide over the top surfaces of the guide block 241 and the plunger cap 240a when the latter is flush with the upper surface of the guide block. The pusher 250 is operated automatically to push the coil down a chute 251 shown 100 in Figs. 3 and 1. The pusher 250 is attached to a rod 252 guided by the bracket 220 and by bracket 253; the right hand end of the rod 252 is pivotally attached at 254 to a lever 255 pivoted at 256 upon the table 40 and carrying a roller 257 cooperating with a cup-shaped cam 258 attached to the shaft 55 as shown also in Fig. 3. The lever 255 is held down by strap 259 and secured by screws 260 to the table 40. A spring 261 attached to the 110 lever 255 and to a post 262 on the table 40 yieldingly urges the roller 257 against the cam 258. The cam operates to retract the pusher 250 and is shaped so as to suddenly release the roller 257 so that the spring 261 115 may operate quickly to move toward the right the pusher in order to eject the coil which has fallen upon the upper surfaces of the plunger cap 240a after the coil was severed from the remaining wire. 120

Insulation stripping mechanism

Referring to Figs. 15 to 19 inclusive, the insulation stripping mechanism 300 is supported by table 301 held in elevated position 125 by legs 302 and adjustably tied to the table 40 by a screw 303 having a handle 304 and threaded through a bar 305 attached to one of the table legs 302 and having a threaded end 306 passing through a plain hole 307 in 130

a bar 308 attached to one of the legs 41 of table 40. The threaded end 306 receives nuts 309 and 310, one on either side of the bar 308. By turning the handle 304 the table 301 may be shifted horizontally along the floor indicated at 311 in Fig. 19. In this way the stripping mechanism may be properly located relative to the coil winding mechanism.

Table 301 is provided with parallel V grooves 312 each receiving a V ridge 313 integral with a base 314 to which the insulation stripping mechanism is attached. The base 314 carries a bar 315 carrying a roller 316 engageable with a cam 317 attached to shaft 44. Roller 316 is yieldingly urged toward cam 317 by springs 318 and 319 connected with a cross bar 320 of table 40 and with a rod 321 extending downwardly from the base 314 through a notch 322 provided by the table 301.

The table 314 supports brackets 325 and 326 which carry pins 327 and 328 respectively upon which rocking frames 329 and 330 respectively are journaled. Frames 329 and 330 rotatably support spindles 331 and 332 respectively carrying on their outer ends pulleys 333 and 334 respectively, and on their inner ends rotary insulation stripping cutters 335 and 336. The pulleys 333 and 334 are connected by belts 337 and 338 respectively with pulleys 339 and 340 respectively, driven by electric motors 341 and 342 respectively, supported by the base 314.

As viewed in Fig. 15 the cutters 335 and 336 rotate clockwise and counterclockwise respectively and engage respectively the lower and upper semi-cylindrical halves of the insulation of the wire and strip off the insulation by a cutting action which takes place during one complete oscillation of the base 314. The wire is guided by tubes 343 and 344 supported by a bracket 345 attached to the base 314. The movement imparted to the base 314 during the insulation stripping operation is such a distance as will cause the portion of wire stripped to be equal in length to the bared portions 33a and 35a of Fig. 1a. The cutter frames 329 and 330 are caused to oscillate about the pivot pins 327 and 328 by a mechanism operated by the shaft 44. Referring to Fig. 3, shaft 44 carries a sprocket gear 350 connected by chain 351 which passes around chain tightening pulleys 352 and 353 associated with the chain tightening device 354 and around a sprocket gear 355 fixed to a shaft 356 supported by brackets 357 attached to legs 302. The shaft 356 carries cams 359 and 360 engaging respectively rollers 361 and 362 carried by levers 363 and 364 respectively, which operate levers 365 and 366 respectively, connected by springs 367 and 368 respectively, with a bracket 369 so that the rollers 361 and 362 respectively, tend to engage

the cams 359 and 360 respectively. The levers 365 and 366 respectively, are connected with slide bars 371 and 372 respectively, guided for horizontal sliding movements by brackets 373 and 374 respectively, having rollers 375 upon which the slide bars rest. The bars 371 and 372 are provided respectively with camming slots 377 and 378 respectively, which receive pins 379 and 380 respectively, attached to vertically slidable bars 381 and 382 respectively, having slotted upper ends respectively for receiving bolts 383 and 384 carried by the bifurcated ends 385 and 386 respectively, of frames 329 and 330 respectively. The cams 317 and 360 are so coordinated that just before the cam 317 begins to operate upon the roller 316 as shown in Figs. 16 and 19, to cause the table 314 to move away from the cam 317, the cams 359 and 360 will have been moved into the position shown in Figs. 16 and 19 in order to cause the cutter spindle frames 329 and 330 to move into position for bringing the cutters 335 and 336 into insulation stripping position. It will be noted that the camming slots 377 and 378 are provided with elongated portions 377a and 378a for the purpose of providing clearance for the pins 379 and 380 respectively, during the time that these pins are caused to travel horizontally when the base 314 moves horizontally first away from the shaft 44 and then toward it. Immediately following a stripping operation the cams 359 and 360 release the rollers 361 and 362 respectively, so that the springs 367 and 368 respectively, may retract the slide bars 371 and 372 respectively to a position such that the camming slots 377 and 378 will cause the pins 379 and 380 to be elevated and lowered respectively so that cutters 335 and 336 will be lowered and elevated respectively away from the wire. In this way the wire is free of the cutters while it is being positively fed to the spindle and while being wound upon the spindle.

Sequence of operation

The sequence of operation of the various mechanisms of the coil producing machine can best be explained with reference to the chart in Fig. 20. The distances measured horizontally represent degrees of rotation of the shaft 44 or crank 207. The base line *ab* represents 360 degrees of crank rotation. The curve ABC represents movement of the rack 205 away from the left, distances of points on the curve *abc* above the base line *ab* representing distances from the left hand position of the rack. Since there is 5 degrees lost motion between the rack and spindle, the spindle will begin rotating at 5 degrees past the normal or left hand dead center position of the crank and will rotate in a counterclockwise direction until 180 degrees during which time the coil is being wound and then will re-

verse and finally come to a stop at 355 degrees.

The V-groove 211 is formed so that its branches have the same slope in order that spindle will travel up and down at the same rate, but is so located with respect to the crank 208 that the spindle is caused to move up from home position during the first 97° of crank rotation represented by curve DE, then down during 97° to 180°, or the following 83°, represented by curve EF, then up during 180° to 263°, or the following 83°, represented by curve FG, and down to home position during 263° to 360°, or during the last 97° of crank rotation represented by curve GH. These curves are of the same slope, hence point F is slightly above the base line GH. This denotes that at the end of the coil winding operation which takes place during the first up and down movements of the spindle represented by curve DEF, the spindle is slightly higher than when at home position denoted by points D or H. This construction therefore provides for locating the stop arm 201 above the stop pin 202 (see Fig. 4) at the end of the period of counter-clockwise rotation of the spindle and at the beginning of the period of clockwise rotation. Thus the spindle stop is non-operative except at the end of the period of clockwise rotation of the spindle. During the movement of the spindle represented by the curve FGH no winding of the wire takes place.

Curve JKLMN represents the movement of the plunger and the dot-dash line curve J'K'L'M' represents the movement of the plunger operating arm 248. It will be noted that this arm has a greater movement than required for operating the plunger the necessary amount so that the spring 254 shown in Fig. 6 will be compressed slightly beyond its initial state so that the upper end of the plunger will follow the lower end of the spindle as indicated by the curve KLM which follows the curve DEF which represents movement of the spindle. Curve OPQR represents the movements of the guide bar 230. Between 180 degrees and 270 degrees represented by the line RO the guide is retracted from the wire. It begins to move at O or at approximately 270 degrees and completes its movement into wire guiding position at P or about 300 degrees. The wire guide remains in position until about 150 degrees when it starts to move away as indicated by line QR, finishing its movement at 180 degrees. Curve STU represents the up and down movement of the shear 222. Knife 222 begins to move at S or about 175 degrees and cuts the wire at T about 190 degrees while the wire guide is retracted. Knife 222 returns to lower position at U or about 200 degrees at which time the ejector operates as indicated by the curve UVW. Point V on the curve at about 220 degrees represents movement of the pusher 250 of Fig. 11 to a

position furthest toward the left for pushing the coil out of the machine. Immediately following the ejection of one coil, the feeding of a wire for forming the start lead of the succeeding coil begins to take place. As soon as the wire guide has moved into operating position as indicated by point P at 300 degrees, the feeding will begin and will take place between 300 and 330 degrees. The locating of the wire guide is accompanied by movement of the bender of the start lead into operating position. The movement of the bender shaft 140 toward the spindle is represented by curve XY. The shaft 140 remains adjacent the winding spindle for a time represented by YZ. ZAA represents movement of the bender shaft 140 away from the winding spindle. Immediately following the positive feeding operation of the wire, the bender begins to turn at 330 or at point BB and continues to turn to bend the wire during the interval represented by the curve BBCC. As soon as the bender is turned to bend the wire it immediately returns to normal position as indicated by the curve CCDD. The return rotation of the bender takes place while the bender is moving out as represented by curve ZAA. The line EEEF represents the interval during which the insulation stripper is operating. It will be noted that the stripper operates between 180 and 290 degrees or immediately following a coil winding operation and before the next succeeding operation of positively feeding the wire from the shear to the spindle.

While the form of embodiment of the present invention as herein disclosed, constitutes a preferred form, it is to be understood that other forms might be adopted, all coming within the scope of the claims which follow.

What is claimed is as follows:

1. Apparatus for making coils of insulated wire for electrical instruments, comprising in combination, means for stripping the insulation from the wire at portions spaced at regular intervals, means for winding the insulated portion of the wire into a coil, and means for severing the wire intermediate the extremities of the stripped portion of the wire whereby the apparatus produces coils of insulated wire having bared end portions.

2. Apparatus according to claim 1 further characterized as having an insulation stripping means consisting of a pair of rotary cutters operating on opposite sides of the wire and a mechanism for causing the cutters to traverse the wire while rotating.

3. Apparatus according to claim 1 further characterized as having an insulation stripping means consisting of a pair of rotary cutters adapted to operate on opposite sides of the wire, arms rotatably supporting the cutters with their axes parallel, brackets rotatably supporting the arms, a base support-

ing the brackets and a mechanism for causing the arms to approach the wire to cause the cutters to engage the wire, for causing the bracket base to make a complete oscillation while the cutters engage the wire and then for causing the cutter supporting arms to recede from the wire.

4. Apparatus for making coils of insulated wire for electrical instruments, comprising in combination, a winding arbor, means for positively feeding the wire to the arbor, means for attaching the wire to the arbor, means for rotating the arbor, means for axially moving the arbor while rotating, means for stripping the insulation from the wire at portions spaced at regular intervals, said stripping means operating before the wire is positively fed to the arbor, and means operating after coiling the wire for cutting the wire across a bared portion to sever the coil from the remaining wire whereby the apparatus produces coils of insulated wire having bared end portions.

5. Apparatus for making coils of insulated wire for electrical instruments, comprising in combination, a winding arbor, means for positively feeding the wire to the arbor, means for bending the end portion of the wire presented to the arbor around a part of the arbor to attach the wire to the arbor for winding purposes, means for rotating the arbor, means for axially moving the arbor while rotating, means for stripping the insulation from the wire at portions spaced at regular intervals, said stripping means operating before the feeding and bending operations, and means operating after coiling the wire for cutting the wire across a bared portion to sever the coil from the remaining wire whereby the apparatus produces coils of insulated wire having bared end portions.

6. Apparatus for making coils of insulated wire for electrical instruments, comprising in combination, a winding arbor, means for attaching the wire to the arbor, means for rotating the arbor first in a wire winding direction, then in a return direction, means for axially moving the arbor while rotating, means operating during the return rotation of the arbor and before the wire-to-arbor attaching means operates for stripping the insulation of the wire at portions spaced at regular intervals, and means operating after the arbor has wound a coil of wire thereon for cutting the wire across a bared portion to sever the coil from the remaining wire whereby the apparatus produces coils of insulated wire having bared end portions.

In testimony whereof I hereto affix my signature.

JOHN Q. HOLMES.
